DESIGN FOR A COMB OR THE LIKE

Joseph C. Foster, Leominster, Mass., assignor to Fosgood Corporation, Leominster, Mass., a corporation of Massachusetts

Application February 6, 1937, Serial No. 67,491

Term of patent 7 years

To all whom it may concern:

Be it known that I, Joseph C. Foster, a citizen of the United States, residing at Leominster, in the county of Worcester, State of Massachusetts, have invented a new, original, and ornamental Design for a Comb or the like, of which the following is a specification, reference being had to the accompanying drawing, forming part thereof, in which:

Fig. 2 is a top plan view thereof.

I claim:—

The ornamental design for a comb or the like, substantially as shown.

JOSEPH C. FOSTER.
